CONTROL MACHINE FOR RAILWAY TRAFFIC
CONTROLLING SYSTEMSJoseph F. Merkel, Rochester, N. Y., assignor
to General Railway Signal Company, Roche-
ster, N. Y.

Application October 16, 1937, Serial No. 169,436

8 Claims. (Cl. 246—3)

This invention relates to control machines for traffic controlling systems, and more particularly pertains to such machines for remotely controlling track switches and signals through the medium of code type communication systems.

It is important in constructing control machines that such machines shall be organized to occupy a minimum amount of space, so that all manually operable devices are located within the most convenient reach of the operator, so that all parts can be readily replaced and inspected, and so that additions to the machine can be readily provided by adding new units to the original machine.

In view of the above, a control machine made up of several units is provided by this invention which has been organized to meet requirements of the above and other conditions.

Other objects, purposes and characteristic features of the present invention will be in part obvious from the accompanying drawings, and in part pointed out as the description progresses.

In describing the invention in detail, reference will be made to the accompanying drawings in which similar reference characters refer to corresponding parts throughout the several views and in which:

Fig. 1 is a front isometric view of a control machine constructed in accordance with the present invention;

Fig. 2 is a plan view of the control machine shown in Fig. 1 with certain of the top covers removed;

Fig. 3 is a side elevational view of one of the units of the control machine shown in Fig. 1;

Fig. 4 is a diagrammatical plan view showing how the independent sections are provided.

With reference to the accompanying drawings and particularly Figs. 1 and 4, a control machine is shown as having been made up of units T (provided with distinctive exponents) assembled about a rectangular shelf S, which can be used as a desk, in such a manner that the control levers and buttons for the control of track switches and signals are mounted on control panels P at the back and at both sides of the shelf S within the most convenient reach of the operator.

The general organization of the units to form one control machine is illustrated in Fig. 4 as having a master unit T¹ at the left of the shelf type desk S, control units T², T³, T⁴, and T⁵ at the back of the desk, and control unit T⁶ at the right of the desk. Each of the control units is provided for controlling track switches and sig-

nals for a particular track layout and houses certain relays and control apparatus associated therewith, while the master unit houses certain relays and apparatus essential for communicating control messages selected by the apparatus in each control unit, to stations at the track layout associated with that control unit.

Due to the particular type of construction of the units, they can be readily replaced without interfering with the structure or operation of the remainder of the machine, thus existing units can be readily replaced by units which conform with the changes made in the track layout associated with those units, for example, unit T³ can easily be removed and replaced by another unit.

Similar units can also be added to the machine at either end or inserted between any of the existing units. If the units are added to the ends of the machine the end cabinets are easily removed and the new units inserted, and if the new units are inserted between units already assembled, for example, between units T³ and T⁴, such changes can easily be made and the desk lengthened or replaced to conform to the particular requirements of practice.

The master unit and the control units are of similar mechanical construction except for the equipment on the control panels, therefore a consideration of the construction of parts of various units in detail is to be considered as typical of the construction for any of the other similar units.

Each of the units, for example, unit T³ (Fig. 3), consists of a channel shaped base 33, having secured thereto, at a front and a rear corner for one side, upright U-shaped supports 29 connected together by a rod at the top. The U-shaped supports are secured to the corners of the base in such a manner that they will rest half on the base of that unit and half on the base of the adjoining unit, thus furnishing a means for securing the units together.

At the front of each base is secured to the front U-shaped support a panel constructed of sheet metal, which has included in it a rectangular control panel P constructed of insulating material. The back of each unit is provided with a rectangular cover 3 (Fig. 1, unit T⁶) which is held securely in place by fasteners 4, and above the rear cover is secured a small rectangular sheet metal panel 30 for completing the enclosure of the back of the unit. A sheet metal cover 12 is provided for the top of each unit.

A channel shaped base member 5 having its

lower edges bent outward so as to occupy a space in the channel of telescoping members 6 is allowed to slide longitudinally in or out of the stationary part of the unit.

5 On the base member 5 is mounted a housing 7 which is rectangular in shape and is constructed of sheet metal, having the back open and having the front enclosed by glass or suitable transparent material secured in suitable frames 8 which are slidable in a horizontal plane within channels secured to the front of the housing. Additional support for the housing is provided by the channel secured to its top and slidable in a horizontal plane within bar 10 which is secured to the stationary part of the unit.

10 15 The relays 11 are plugged into bases of insulating material such as bakelite, which are secured to supports fastened to the housing in such a manner that the bases form a back for the relay cabinet so that the relays can be readily inspected or replaced when the windows are open and that the relays are enclosed in a dust proof enclosure when the windows are closed.

20 25 In the top of each of the units, for example units T¹ and T² (Fig. 2), is mounted a terminal board 31 secured to the U-shaped supports for that unit and it is readily accessible when the cover 12 is removed from the top of the unit.

20 30 Each unit has secured to the front of that unit a control panel P which is hinged at the bottom to allow it to swing out and in a downward position (for example, unit T³ shown in Fig. 3) to allow inspection and replacement of electric lamps, control switches and the like.

35 40 Each unit for the control of track switches and signals (units T², T³, T⁴, T⁵ and T⁶) has a panel P constructed of suitable insulating material which has constructed thereon as shown for unit T³, for example, a miniature track diagram 13 with indicator lamps 14 for the track sections of the track layout for which the unit is provided.

45 50 Control levers 15 for controlling the signals are provided below the miniature track diagram, and when the handle of the lever is in a vertical position the signals associated with that lever are in their normal at stop position, when that lever is operated 90 degrees from normal to the right, signals for governing traffic in a direction to the right can be cleared, and when the lever is operated 90 degrees from normal to the left, signals for governing traffic in a direction to the left can be cleared. Indicator lamps 16 are provided above the signal control levers for indicating the direction for which signals are cleared, the lamp at the right being illuminated when a signal is cleared for traffic to the right, and the lamps at the left being illuminated when a signal is cleared for traffic to the left.

55 60 Below the signal control levers is located levers 17 for controlling the track switches for the interlocked group with which the signals controlled by the above signal levers are associated. When the handle of the switch control lever is in a vertical position the associated track switch is caused to be operated to a normal position, and when the control lever is operated to a right horizontal position the associated track switch is caused to be operated to a reverse position. Included within the center of the switch control levers is a normally dark indicator lamp 18 which is illuminated only when the track switch is out of correspondence with the position of that switch control lever.

65 70 75 A start push button 19 is located below the switch or signal levers and the depression of that

button starts the operation of the system to transmit the controls as selected by the contacts associated with the levers above the button.

75 The units house control apparatus for a selector type system for communicating controls to stations at track layouts in the field, such, for example, as the system disclosed in Patent No. 2,082,544, dated June 1, 1937, granted to Judge et al.

10 15 20 25 In this type of communicating system different series of electrical impulses, commonly called cycles, are selected as a result of the operation of the control switch on the control panel, and are transmitted to the field stations through the medium of the relays in the master unit, the control units being essential for selecting the impulses, and the master units being essential for transmitting the impulses. Similarly, in a reverse order, indications are received by the master unit, from the field stations, and are selected 20 and indicated at the control unit associated with the function involved.

25 30 35 Thus, in order to provide electrical controls between the master unit and each control unit, a cable of wires is provided from the master unit to each of the control units, such, for example, as cable 35 (Fig. 2) extending from the terminal board for the master unit T¹ to the terminal board for the control unit T².

35 40 45 The control panel for the master unit differs from the control panels for the control units only in the apparatus mounted thereon, of which at the left is a control switch 20 for setting the communicating system into operation to give a special signal for calling the maintainer, when operated to an upward position, and for setting the communicating system into operation for rechecking indications, when operated to a downward position. The grouping of the units about the desk is particularly convenient and necessary 40 for operating the recheck switch, because it is also necessary to depress the start button on the control panel of the control unit for which the indications are to be rechecked.

45 50 55 The control switch 21 on the control panel of the master unit at the right is used to suppress the transmission of indications from a field station if such suppression is desirable, such as at times when a field station improperly continues to transmit indications to the exclusion of further use of the communicating system, when that control switch is operated to an upward position, and it is used when operated in a downward position to stop the transmission of controls after such transmission has been started 55 by the depression of a start button.

60 65 70 A cycle counter 22 is located at the lower left-hand corner of the master unit panel for recording the number of operations of the system, and above it is located an indicator lamp 26 which is illuminated whenever the communicating part of the system is in operation.

75 80 85 90 At the front of the left wing of the control machine and adjacent to the master unit is a vertical rectangular cabinet 23 constructed of sheet metal, and having a door 24 in the front which opens outward to the left. Within the cabinet is located a test panel 32 which is so constructed that it is hinged to open outward to the right through the opening in the front 70 on the cabinet. This particular housing arrangement allows the test panel to be closed from view except when being used, and also allows readily the replacement of parts and maintenance of the equipment.

The test panel is constructed of suitable insulating material and it has located thereon meters, fuses, indicator lamps, and whatever testing equipment is required in practice. The testing apparatus shown on the control panel includes, starting at the top of the panel, a voltmeter, and an ammeter with shunt switches, control and indicator line variable resistors, having lock nuts for holding them in a set position, fuses, cycle indicator lamps, hand step switch for governing the operation of each step, and a terminal board.

A rectangular vertical sheet metal housing 25 similar in size and shape to the cabinet for the test panel is secured adjacent to the unit at the right hand end of the shelf. This housing provides a section through which cables can extend from the terminal boards to a wire chase in the floor, as well as providing an end panel for completing the enclosure of the equipment.

The space between the back corners of the units nearest the back corners of the shelf is enclosed by a sheet metal panel, and a narrow panel is also provided between corresponding front corners of those units. These corner sections are constructed in a similar manner to the construction of the stationary part of each unit except that a hole 34 is provided in the bottom of that section to provide an outlet for 30 the cables to a wire chase in the floor.

The shelf type desk S is constructed of sheet metal, and the length of S is determined by the number of units included in the control machine. The top of the desk is flat with the back corners beveled to fit the inside corner panels, and the sides are shaped in the form of supporting brackets which are secured to the U-shaped supports for the front outside corners of the end units at the back of the desk by 40 screws 36.

Having thus described each unit in detail it is obvious that as many units as are required in practice may be assembled about the shelf S and secured at the bottom by a strip of angle iron 27 at the front and back, and secured at the top by screws 28 to the upright U-shaped pieces which overlapped the sections.

In summing up some of the characteristic features of the control machine as provided by this invention, it will be noted that the machine has been made compact by utilizing all of the space within the cabinet for control equipment, thus allowing the installation of machines in buildings where the available space for those machines is limited, all of which compactness in no way limits accessibility of the apparatus for inspection, replacement and repair.

The use of the sliding relay cabinet provides a relay capacity limited only by the depth of 60 the machine, all of which relays along with their wiring connections are readily accessible.

The means provided for mounting the terminal boards for each unit is such that, when the units are placed side by side, the terminal boards 65 for the individual units form, in effect, one large terminal board all in one plane which is readily accessible along with cables extending between the terminal boards for certain of the units.

The units are so arranged about the desk that 70 their control panels are within convenient reach of the operator and that the operator can also reach and operate control apparatus on a number of units simultaneously. The control panels 75 are also arranged to open outwardly to provide

convenient inspection and replacement of the apparatus associated therewith.

The test panel is in a convenient position to allow the operator to watch the indicator lamps on the control panels while testing, is closed from view when not in use, and it is readily accessible for repairs and the replacement of parts from both sides of the panel and at a convenient height from the floor.

The units are of a size and shape which can 10 be easily transported through narrow doorways and passageways and which can be easily assembled together to make one control machine, or which can easily be added to or inserted between other similar units from time to time as 15 required in practice.

Having described a control machine constructed and arranged according to the present invention, it is desired to be understood that this form is selected to facilitate in the disclosure of the invention rather than to limit the number of forms which it may assume; and, it is to be further understood that various modifications, adaptations and alterations may be applied to this specific form shown to meet the requirements of 25 practice, without in any manner departing from the spirit or scope of the present invention except as limited by the appended claims.

What I claim is:

1. In a control machine for traffic controlling 30 systems for railroads, a box like control unit, a panel hinged at the front of said unit to swing outwardly and downwardly, control levers and indicating lamps supported by said panel and movable therewith, an assemblage of relays in a 35 cabinet slideably supported in said unit to be withdrawn at the back to give access to the relays, a stationary terminal board disposed horizontally at the top of said unit, flexible looped wire cables interconnecting said terminal board with the 40 control levers and indicating lamps on said panel and with the relays in said cabinet respectively, and removable covers for the top and back of said unit affording access to said terminal board and said relay cabinet respectively. 45

2. A control machine for railway traffic control systems of the code type comprising, a single master unit housing the apparatus of the code communication system common to a number of switches and signals; a plurality of like control units each including a track diagram, control levers and indicating lamps belonging to a portion of track equipment with a predetermined number of track switches and associated signals; a shelf-type desk; means for detachably securing said control units together side by side along the back and sides of said desk with said master unit at one end, so that all are within sight and reach of an operator at the front of the desk, a relay cabinet removably mounted in said master 50 unit and in each of said control units, stationary terminal boards associated with said master unit and each of said control units, flexible looped cables interconnecting the several relay cabinets with their respective terminal boards, and wires 55 extending between said terminal boards to provide the circuits interconnecting the relays of said master unit with the control levers and relays of the several control units. 60

3. A control machine for traffic governing 70 systems for railroads comprising, a plurality of similar control units adapted to be assembled and detachably secured together in a row in varying numbers, each of said control units including a control panel pivoted to swing forwardly and 75

- downwardly, manually operable switch and signal levers for a predetermined number of switches and associated signals supported by said panel, a miniature track diagram of a portion of track 5 including such predetermined number of track switches and signals, indicating lamps on said panel associated with said control levers and said track diagram, an assemblage of relays in each unit flexibly and electrically connected with said 10 control levers and indicating lamps, and corner sections adapted to be detachably secured to said control units, each corner section being also adapted to have a control unit attached to the front thereof, whereby any desired number of 15 control units may be arranged in a row interconnected by said corner sections with their attached control unit so as to provide a general U-shape arrangement.
4. A control machine for centralized traffic 20 control systems of the code type comprising, a plurality of like open sided units adapted to be detachably connected together side by side in angularly disposed rows, corner sections attachable to the sides of any one of said units to pro- 25 vide for assembling and closing in different numbers of said units in the angularly disposed rows, one of said units being a master unit containing the apparatus of the code communication system common to the various switch and signal locations, the other units being control units each 30 including a control panel disposed vertically at the front and pivoted to swing inwardly and downwardly to the horizontal, an assemblage of relays in a cabinet slideably supported in each 35 unit to be withdrawn from the back and afford ready access to said relays, a horizontally disposed stationary terminal board at the top of each unit, movable covers for the top and back of each unit to give access to the relay cabinet and terminal board thereof, flexible wire cables 40 extending from each relay cabinet to the terminal board of the corresponding unit, and a flexible wire cable extending from the control panel to the terminal board of each control unit.
- 45 5. A control machine for traffic controlling systems for railroads comprising, a plurality of like control units each including a control panel for a predetermined portion of track and housing the necessary relays for such portion of track, said units being secured to each other side by side in a row by overlapping rigid supports, a rigid support extending horizontally across the front and back of said row of units, a terminal board at the top of each unit for receiving wires extending 50 to the control panel and relays of that unit, and separate removable covers for the top of each unit giving access to its terminal board.
- 55 6. A control machine for traffic governing systems for railroads, comprising, a shelf-type desk, a plurality of like interchangeable control units 60 detachably assembled about the rear edge and the two ends of the desk and supporting said desk, each unit having a support which overlaps and is secured to the adjacent unit, each unit having a control panel at the front hinged to swing downwardly toward the desk, a relay cabinet mounted in each unit to slide longitudinally out of the back of that unit, separate removable covers for the backs of said units, and means rigidly connecting said units together at the front and the back at points not interfering with the outward movement of the hinged panels or sliding movement of the relay cabinets.
7. A control machine for traffic governing systems for railroads, comprising, a shelf-type desk, 15 a plurality of like interchangeable control units detachably assembled about the rear edge and the two ends of the desk and supporting said desk, each unit having a support which overlaps and is secured to the adjacent unit, each unit 20 having a control panel at the front hinged to swing downwardly toward the desk, a relay cabinet mounted in each unit to slide longitudinally out of the back of that unit, separate removable covers for the backs of said units, and means rigidly connecting said units together at the front and the back at points not interfering with the outward movement of the hinged panels or sliding movement of the relay cabinets, a master unit 25 at one end of the desk and rigidly connected to the control units, electrical connections between the master unit and each of the control units.
8. A control machine for traffic governing systems for railroads, comprising, a shelf-type desk, 30 a plurality of like interchangeable control units 35 detachably assembled about the rear edge and the two ends of the desk and supporting said desk, each unit having a support which overlaps and is secured to the adjacent unit, each unit having a control panel at the front hinged to swing downwardly toward the desk, a relay cabinet mounted in each unit to slide longitudinally out of the back of that unit, separate removable covers for the backs of said units, and means rigidly connecting said units together at the front and the back at points not interfering with the outward movement of the hinged panels or sliding movement of the relay cabinets, a master unit 40 at one end of the desk and rigidly connected to the control units, electrical connections between the master unit and each of the control units, 45 a test unit at the end of the desk and rigidly connected to the master unit and having a test panel parallel with the front edge of the desk, a door covering the test panel and pivoted to swing away from the desk, the test panel being pivoted to swing toward the desk to bring its face 50 parallel with the edge of the desk.
- 55

JOSEPH F. MERKEL 60
